PARKING ATTACHMENT FOR AUTOMOBILES

Helodoro Santa Coloma, New York, N. Y.

Application March 28, 1951, Serial No. 218,024

3 Claims. (Cl. 180—1)

1

The invention here disclosed relates to the problem of parking automobiles at the curb where space is too limited for maneuvering in the usual way.

General objects of the invention are to provide a mechanism which, after the front wheels of the car have been entered in the space, can be actuated to lift and swing the rear end of the car into the allotted space, parallel with the curb.

Particularly it is a purpose of the invention to provide a mechanism of this character which can be applied as an attachment to a standard make of car and derive power for actuating the same from the drive gear of the car.

More specifically it is an object of the invention to provide this parking mechanism in a form which can be applied to the differential housing of the rear axle and take off power for effecting the lateral shifting of the car from the ring gear of the differential, utilizing the forward and reverse drive controls to accomplish the lateral traversing movement in either direction required.

These objects are attained in part by providing a special cover for the differential housing which can be substituted in place of the regular cover and which forms a base for and carries the lifting and traversing mechanism and locates the pinion by which the power is taken off in meshing engagement with the main gear of the differential.

Other desirable objects and features of the invention are set forth and will appear in the course of the following specification.

The drawing accompanying and forming part of the specification illustrates a present preferred embodiment of the invention. Structure, however, may be modified and changed in various ways, all within the true intent and scope of the invention as hereinafter defined and claimed.

Fig. 1 in the drawing is a diagram illustrating the problem of parking a car in a slightly more than car length space left between two vehicles standing at a curb, with arrows showing how with the present invention, a car may be headed into such a space and then swung laterally into parked position;

Fig. 2 is an elevation showing the mechanism applied to the rear axle housing, the full lines showing the lifting and shifting mechanism fully lowered, and the broken lines showing this mechanism raised into inactive position at the back of the axle housing;

Fig. 3 is a broken vertical sectional view of the jack construction on substantially the plane of line 3—3 of Fig. 2 but showing the driven road

2

wheel appearing at the left in Fig. 2 and the shaft and gearing for driving the same;

Fig. 4 is a broken horizontal sectional detail as on substantially the plane of line 4—4 of Fig. 3.

The drawing may be considered as illustrating a car of more or less conventional design having a rear axle housing 1, with an enlargement 8 enclosing the differential gears such as the main or ring gear 9 and the drive pinion 10 of the propeller shaft.

A conventional differential housing such as shown usually has a removable cover at the back secured by bolts at 11.

The present invention contemplates that this regular cover will be removed and be replaced by a special cover carrying the mechanism to be described, and possibly secured by the same bolts 11 which fasten the plain cover in place.

This special replacement cover is designated 12 and performs all the functions of the normal cover, but additionally it carries a bearing 13 for a shaft 14 mounting a pinion 15 in mesh with the main gear 9 of the differential at a point back of the axle and more or less opposite the propeller shaft pinion 10.

This provides a power take-off from the unused portion of the main differential gear which can be utilized for effecting the traversing movement, one way or the other, according to which way the differential gear is driven from the transmission of the car.

The special differential cover 12 is constructed with a hub extension portion 16 concentric to the added pinion shaft 14 and designed to form a bearing and swivel support for the sleeve or hub portion 17 which forms the base structure for the lifting jack.

The jack is designated 18 and is shown as of the hydraulic type involving an angularly directed cylindrical extension of the mounting sleeve 17 and a piston 19 operating in the cylinder, having a rod 20 extended laterally at 21 to carry the supporting and lateral shifting wheels 22, 23.

One or both wheels 22, 23, may be driven to effect the lateral shifting movement.

For greater simplicity only one of these wheels need be driven.

In the illustration the wheel 22 is shown driven from the pinion shaft 14 by bevel gear 24 in mesh with bevel gear 25 on the upper end of a shaft 26 having a sliding telescopic connection at 27 with a bevel gear 28 journaled in a bearing 29 forming part of the mounting for the wheel 22 and meshing with a pinion 30 on the axle of that wheel.

This telescopic drive shaft connection enables the lateral traversing wheel to be raised or lowered by the jack without engaging or disengaging any gears.

The gearing for driving the lateral traverse wheel, however, is normally disengaged and inactive during the usual driving operations of the car. This is accomplished by providing a shiftable clutch collar 31 keyed at 50, Fig. 3, on the pinion shaft 14 in position to couple and uncouple the pinion 24 in respect to that shaft.

Control of this clutch is effected in the present disclosure by an electromagnet 32 for operating the fork 33 controlling the movable clutch element 31. A spring may be provided for uncoupling this clutch and the magnet used to hold the clutch engaged only for the short periods for which it may be used.

The jack structure is swung on its swivel mounting from an inactive position at the back of the rear axle, shown by the dotted lines in Fig. 2, down into the active lifting and traversing position by means consisting, in the present disclosure, of a hydraulic cylinder 34 swiveled on the axle housing or other available support, at 35, and containing a piston 36 having a rod 37 pivotally connected at 38 with an angularly projecting arm 39 of the mounting sleeve 41.

This hydraulic power cylinder has connections 40, 41, by which actuating fluid may be admitted and exhausted, with suitable valve mechanism for effecting such controls.

Similarly, the hydraulic jack has suitable connections 42, 43, and controls, with pump mechanism for both hydraulic elements, power or hand-driven, as desired.

The dotted lines in Fig. 2 show how the lifting and traversing mechanism is stowed away in elevated position at the back of the rear axle housing so as not to interfere with all normal driving operations of the car.

To effect parking in a small space between adjoining cars or other objects such as represented in Fig. 1, the car equipped with this invention may be driven head-on into such space and the rear end then swung into the space, close up to the curb, by first operating power cylinder 34 as in Fig. 2, to swing the jack down into vertical position, and then operating the jack to lower the side traverse wheels 22, 23, in engagement with the road surface and to effect lifting of the rear end into supported relation on said laterally directed wheels.

With the wheels 22, 23, supporting the rear end of the car, the magnet 32 may be energized to clutch the pinion 24 on shaft 14, and then the clutch or other control governing forward and reverse drive of the car may be actuated to effect forward or reverse turning of the differential gear 9 for operating the driven traverse wheel 22 to swing the car end in the direction selected and determined by the direction of rotation of the differential gear.

To drive off the differential gear in this way, such gear should be free to be turned by the engine in either direction.

To assure this condition the line 44 supplying the hydraulic actuating fluid to one of the rear wheel brakes 45, Fig. 2, may be equipped with a magnet valve 46 or equivalent connected to be actuated to release this one brake when the mechanism is set, ready to effect lateral shift of the car.

Thus this valve 46 may be arranged to be actuated to release this one brake at the time

when magnet 32 is energized to clutch the gearing for driving the lateral shifting wheel. Then with one wheel free to turn, the differential gear will be free to rotate either for forward or reverse drive and as a consequence the supporting road wheel 22 may be driven to swing the rear end of the car either to left or right, as required.

The mechanism disclosed can all be mounted on a substitute differential cover plate and hence be readily applied as a complete parking attachment for a car of conventional construction. The power for effecting the actual shifting is taken off from the unused back portion of the main differential gear and is controllable to shift in either direction through the conventional forward and reverse drive controls of the car.

While a jack of the hydraulic type has been illustrated, it is contemplated that various mechanical forms of jacks may be employed.

What is claimed is:

1. A parking attachment for automobiles comprising a substitute differential cover plate constructed to replace the cover plate normally present on the differential housing of a conventional motor car and in that position to cover the main differential gear present in such cars, said cover plate having a rearwardly extending hub, a jack having a companion hub portion swiveled on said cover plate hub and enabling said jack to be swung from a raised to a lowered position at the back of the differential housing, said jack having an extensible member and a road wheel on said extensible member and whereby the jack in the lowered position may operate to lift the differential housing on said road wheel, means connected with said jack for rocking said jack on the hub of the cover plate to effect lowering of the jack into operative position and raising of the jack into inoperative position, a power take-off shaft journaled in the cover plate and extending rearwardly in concentric relation through the cover plate hub, a pinion on the inner end of said shaft for driven engagement with the main differential gear present in conventional motor cars, a road wheel driving shaft journaled on the jack, an extensible driving connection extending from said road wheel driving shaft to said road wheel, and drive gearing from said take-off shaft to the upper end of said road wheel driving shaft and including clutch means for drivably connecting and disconnecting said power take-off shaft and road wheel driving shaft and so that said road wheel may be operated in opposite directions from the main differential gear according to the direction in which said main differential gear is operated.

2. A parking attachment for automobiles comprising a substitute differential cover plate constructed to replace the cover plate normally present on the differential housing of a conventional motor car and adapted to be positioned thereby over the main differential gear normally present in such housing, said cover plate having a rearwardly extending hub, a jack having a companion hub portion at the upper end of the same swiveled on said cover plate hub and enabling said jack to be swung from a raised to a lowered position at the back of the differential housing, said jack having an extensible member below said hub portion, road wheels carried by said extensible member and spaced to opposite sides of the hub center and whereby when lowered into engagement with the road said wheels will support the rear axle in a man-

ner free to swivel about the hub center, means connected with said jack for rocking said jack on the hub of the cover plate to effect lowering of the road wheels into operative relation and raising of said road wheels into inoperative position, gearing for driving at least one of said road wheels from the main differential gear including a power take-off shaft journaled in the cover plate in concentric relation to the cover plate hub, a pinion on the inner end of said shaft for driven engagement with the aforementioned main differential gear, drive gearing extending from said shaft to at least one of said road wheels and control means interposed in said drive gearing for rendering said drive gearing operative or inoperative.

3. A parking attachment for automobiles comprising a substitute differential cover plate constructed to replace the cover plate normally present on the differential housing of a conventional motor car and adapted to be positioned thereby over the main differential gear normally present in such housing, said cover plate having a rearwardly extending hub, a jack having a companion hub portion at the upper end of the same swiveled on said cover plate hub and enabling said jack to be swung from a raised to a lowered position at the back of the differential housing, said jack having an extensible member below said hub portion, road wheels carried by said extensible member and spaced to opposite sides of the hub center and whereby when lowered into engagement with the road said wheels will support the rear axle in a manner free to swivel about the hub center, means connected with said jack for rocking said
